CONTAINER

Filed May 4, 1942

INVENTOR:
LEON E. DENISON,

BY *George Kacine*
ATTORNEY.

UNITED STATES PATENT OFFICE

2,340,651

CONTAINER

Leon E. Denison, Richmond Heights, Mo., assignor to Brooks Paper Company, St. Louis, Mo., a corporation of Missouri

Application May 4, 1942, Serial No. 441,657

4 Claims. (C.I. 229—7)

This invention relates generally to containers and, more particularly, to a certain new and useful improvement in containers of bag, carton, or other such type commonly employed in the retail merchandising of rice, sugar, salt, and other flaked, granular, pulverized, or flowable edibles, or other materials or substances.

My invention has for its object the provision of a container of the type mentioned with a pouring-outlet and a closure-assembly therefor uniquely capable of repeated manipulation for enabling the house-wife to conveniently remove selected portions of the contents and meanwhile preserving and protecting the gradually lessening contents until the confainer has been entirely emptied of its contents.

And with the above and other objects in view, my invention resides in the novel features of form, construction, arrangement, and combination of parts presently described and pointed out in the claims.

In the accompanying drawing—

Figure 1 illustrates in elevation a rice-packed flexible bag or container equipped with a pouring-opening or outlet and closure in accordance with and embodying my invention, the container being partly broken away and in section and the pouring-outlet being closed;

Figure 2 is an enlarged fragmental longitudinal sectional view, taken approximately on the line 2—2, Figure 1, of the container with its contents removed;

Figure 3 is an enlarged fragmental transverse sectional view of the container taken approximately on the line 3—3, Figure 1;

Figure 4 is an elevational view of the combined closure-providing and reinforcing member of the container;

Figure 5 is an enlarged fragmental elevational view of the container with its outlet-closure in open contents-dispensing position;

Figure 6 is an elevational view of a container equipped with a slightly modified pouring-opening and closure embodying my invention;

Figure 7 is an enlarged longitudinal sectional view taken approximately on the line 7—7, Figure 6;

Figure 8 illustrates the container of Figure 7 equipped with an outlet-closure assembly for location and attachment in operable association with its pouring-outlet; and

Figure 9 is a perspective view of the closure assembly of my invention applicable to the dispensing-opening or outlet of the containers of Figures 7 and 8.

Referring now more in detail and by reference characters to the accompanying drawing, which illustrates practical embodiments of my invention, A, Figures 1 to 5, both inclusive, designates any preferably flexible standard container, such, for instance, as a paper bag, which, while not here shown, is folded and interfolded at its one or base-end in any suitable manner and, at its other end or top, is, when filled with its contents, in the present instance, a granular product, such as rice B, is also folded and interfolded, as at 1, as will be well understood.

During the formation of the bag A, however, a member C, which is constructed preferably of any suitable relatively light-weight bendable paste-board, card-board, or the like, and which may have any suitable contour, is adhesively, as at 5, fixed to and upon the sheet or section of material of which the bag A is formed at such 15 selected location that, the construction of the bag A being completed, the member C will be presented on a wall, and preferably adjacent the upper or open end, of the finished bag. In the present instance, the member C is in the formation 20 of a disk and, resulting from the location thereof during formation of the bag, appears upon a wall 2, and adjacent the upper end of, the bag, as best seen in Figure 1.

The member C being so located, the member C 25 and the bag wall 2 are registrably and as a unit circularly die-cut or kerfed, as at 3, for approximately 280° on a selected radius. The bag A is thereby provided with an outlet a of circular conformation and of a selected diametrical dimension for pouring or discharging the particular 30 contents of the bag or container A, and, at the same time, the bag A is also thereby provided with a so-called flap c for closure of such outlet a, as shown. The flap c, which includes a portion 35 of the member C, as well as the underlying adhesively attached kerfed portion of the bag wall 2, is thus integrally joined, as at 4, to the respective member C and wall 2, and such portion 4 is preferably suitably scored, as at c', during the 40 kerfing of the member C for facilitating bending thereof in any hinge movements of the flap c, as presently fully appears.

Then, as at 6, applied at an end to and upon the container A adjacent a portion of the margin of the member C, is a section of so-called "tacky" or adhesive tape or other like material D of suitable width, as best seen in Figure 1, and of a length to extend adhesively crosswise or diametrical over and upon the member C and the flap c and for adhesive attachment as its oppo-

site end, as at 7, to and upon the container wall 2, as also best seen in Figures 1 and 2. It may be here stated that the ribbon or strip D is preferably of the form or variety commonly known as "Scotch tape," which has the inherent property of retaining its adhesive characteristics indefinitely, permitting frequent separation, on proper pull, of the tape from, and readherence of the tape to, a designated surface.

Hence, in practice, the strip D functions normally to firmly and securely retain the flap c in full seated closure position in the outlet a and in flushwise registration with the member C, as best seen in Figures 1, 2, and 3. However, under proper pull, the strip D may be detached at its end 7 from the container-wall 2 and then, as the strip D is flexibly or hingedly pulled upwardly away from the container A, the adhesively attached flap c is hingedly lifted along the scoring c' from its normal flushwise seating in the kerfed portion 3 of the member C and removed from its closure position in the outlet a, as best seen in Figure 5, and pouring of the granular or other flowable contents B thereby freely permitted to the extent desired, the flap c being again carried to full closure-position in the outlet a and into flushwise registration with the member C on reverse swinging or hinged movement of the end-portion 7 of the tape D and reattachment thereof to and upon the container wall 2.

Preferably, though not necessarily, the tape D at its upper end 6 may be overlapped and additionally secured to the container A by means of a strip E having permanent adhesive qualities, which may continue over the folds 1 and for some distance therebeyond, as shown in Figure 2, thus serving also as a sealing agent for the package as a whole.

In the structures illustrated in Figures 6 to 9, both inclusive, a flexible or paper container A' is housed within an enclosing paste-board, cardboard, or other such rigid or semi-rigid carton F, which is preferably provided in a wall f thereof with an elliptical or otherwise contoured sight-opening 8, and to which carton F is, as shown in Figure 8, accessibly attached a unit G, which includes a "tacky" strip D' and a closure-flap c''. Accordingly, in practice, the house-wife, under instructions displayed on the carton F, will at the opening 8 suitably puncture the wall 2' of the housed bag A', then first detach the unit G from the container F, and then locate and attach the same upon the carton-wall f, so that the strip D' may be repeatedly used as a means for manipulating the flap c'' to seat the same in the cut-out 8 in closure position over the housed container A' or, as seen in Figure 7, remove the same from such seated position as may be desired until the package has been entirely emptied of its contents. Of course, the carton F may be supplied to the

house-wife with the unit G properly located thereon with respect to its opening 8, as shown in Figure 6, with appropriate manipulating instructions displayed thereon.

5 The structure is inexpensive, extremely simple, most easily and conveniently operable, and exceedingly efficient in the performance of its intended functions, and it should be understood that changes and modifications in the form, construction, arrangement, and combination of the several parts of the structure and closure-assembly may be made and substituted for those herein shown and described without departing from the nature and principle of my invention.

10 15 Having thus described my invention, what I claim and desire to secure by Letters Patent is:

1. In combination, a container, a member fixed flatwise on a wall of the container, said member and the container-wall being kerfed as a unit for providing a discharge outlet through both said member and the container-wall and a two-ply flap for seating in said outlet for closure thereof, and means for manipulating the flap to and from its seat.

20 25 2. In combination, a container having a wall constructed of flexible material, a member of bendable material fixed flatwise on said container-wall, said member and the container-wall being kerfed as a unit for providing a discharge outlet and an integrally joined two-ply flap for seating in said outlet for closure thereof, and means for manipulating the flap to and from its seat.

30 35 3. In combination, a container having a wall constructed of flexible material, a member of bendable material fixed flatwise on said container-wall, said member and the container-wall being kerfed as a unit for providing a discharge outlet and an integrally joined two-ply flap for seating in said outlet for closure thereof, said flap comprising a portion of the container-wall and a portion of said member, and means including a section of tape connected to said member and to said flap for hingedly manipulating the flap to and from its seat.

40 45 4. In combination, a container having a wall constructed of flexible material, a member of bendable material fixed flatwise on said container-wall, said member and the container-wall being kerfed as a unit for providing a discharge outlet and an integrally joined two-ply flap for seating in said outlet for closure thereof, said flap comprising a portion of the container-wall and a portion of said member, and means including a section of tape having adhesive connection intermediate its ends with the flap and adhesive connection at an end with the container and adapted for detachable connection at its other end with the container for manipulating the flap to and from closure position.

60 LEON E. DENISON.
